VOTING MACHINE

Alvin N. Gustavson, Jamestown, N. Y., assignor
to Automatic Voting Machine Corporation, a
corporation of Delaware

Application March 26, 1938, Serial No. 198,302

5 Claims. (Cl. 20—3)

This invention relates to an improvement in voting machines and more particularly to a mechanism adapted to assist voters in unlocking the machines for voting.

5 The type of voting machine to which the present invention is applied, is provided with a lever located adjacent the top center of the machine and movable by a voter to draw a set of curtains or other enclosure about a voter and to unlock 10 or release the indicators on the keyboard of the voting machine. The patent of Gillespie No. 995,342 illustrates a voting machine of the general type to which the present invention may be applied. In order that a voter may be completely 15 enclosed by the curtains when he has taken a position in front of the keyboard of the voting machine, it is necessary that the curtain operating lever be swung about its pivot from one side of the machine to the other. Substantially at the 20 end of travel in a direction to draw the curtains and enclose a voter, the lever is adapted to actuate certain elements in the machine which unlock or release the voting indicators. The lever moves comparatively freely until it commences 25 to actuate the indicator release mechanism. From this point to the end of travel, a matter of a few inches, more effort is required to move the lever. It was found that many voters mistakenly believed the machine to be unlocked 30 when the curtains were fully drawn and therefore failed to move the lever the full distance necessary to unlock the voting indicators. Thus, when a voter attempted to move the indicators he found them to be locked and the election official 35 in attendance at the machine was called. If the official was familiar with voting machines and could readily ascertain that the voter had himself failed to unlock the machine by not completing the cycle of movement of the lever, he 40 could give the necessary instructions. In some instances, however, election officials were not familiar with voting machines and it became necessary to call in a repair man to ascertain and correct the trouble. This procedure, of course, 45 took considerable time, temporarily prevented use of the machine, and greatly interfered with and slowed down voting.

The present invention is directed to and has 50 for an object the provision of means for assisting a voter in moving a curtain closing lever the distance required to release or unlock a machine for voting.

Another object of the invention is to provide 55 a mechanism adapted to assure a voter's unlock-

ing a machine for use, subsequent to closing the curtains.

Another object of the invention lies in the provision of means for moving the curtain closing lever through its final travel for the purpose of 5 unlocking the voting machine for use.

Other and further objects of the invention will be more fully understood from a consideration of the following specification, taken in conjunction with the accompanying drawing and in which:

Fig. 1 is a fragmentary plan view of a voting machine with one modification of the invention applied to the curtain closing and machine unlocking lever thereof;

Fig. 2 is a fragmentary plan view showing the 15 lever in the position occupied when the curtains are closed and the voting machine is about to be unlocked;

Fig. 3 is a view similar to Figure 2 showing the lever in the position occupied when the curtains 20 are closed and the machine is unlocked for voting;

Fig. 4 is a vertical sectional view taken substantially on the line 4—4 of Figure 1;

Fig. 5 is a horizontal sectional view taken substantially on the line 5—5 of Figure 4, and, 25

Fig. 6 is a vertical sectional view taken substantially on the line 6—6 of Figure 4.

Referring to the drawing, the reference numeral 10 is employed to designate a portion of a voting machine. The voting machine includes 30 a top 11 on which is located a reinforcing plate. Within the machine and directly beneath the plate 12 is a further plate 13. Plate 13 is somewhat spaced from the top 11, being held in place by pins 14 which are riveted or otherwise secured 35 to plate 12. Concentric openings are provided centrally of plates 12 and 13 and top 11. A shaft 16 projects through these openings and is fitted with a pair of vertically spaced bars 17 and 18. The bar 17 is formed with a collar 19 and is secured to the shaft 16 by a pin 21. The bar 18 is formed with a collar 22 through which a pin 23 projects to secure it against rotation with respect to the shaft 16. Bars 17 and 18 are vertically aligned and connected at their ends by 45 means of pins 24 and 26. The forked end 27 of a rod 28 engages the pin 24. The forked end 29 of a further rod 31 engages pin 26. Rods 28 and 31 are movable transversely of the machine toward or away from each other as the shaft 16 is 50 rotated. These rods are adapted, when moved, to actuate certain mechanisms in the machine such as, those for recording ballots and resetting the machine for further balloting.

A pair of diametrically opposed openings are 55

made in the plate 13. Concentric with these openings are further openings in the top 11 and plate 12. Pins 32, having transverse slots 33, are projected through the openings of plates 12 5 and 13 and top 11. The small ends 34 and 36 of a pair of bars 37 and 38 project into the slots 33 of the pins 32 and are adapted, under certain circumstances of operation of the device, to move the pins upwardly to project through and above 10 the plate 12.

That portion of the shaft 16 projecting above the plate 12 is adapted to mount a disk 39. This disk may be secured to the shaft 16 by means of a pin 41 that projects through a collar 42 and the shaft. The circumferential edge of the disk 39 is cut away at one point to provide an inclined surface 43. A pair of adjacent openings 44 and 46 are made in the disk and, under certain conditions of operation, register with one or the other of pins 32, permitting said pins to be elevated by movement of their respective bars 37 20 and 38. Secured to the plate 12 adjacent the circumferential edge of the disk 39 is a pin 47. This pin serves as an off-center pivot for an arm 25 48. The short end of the arm 48 is fitted with a roller 51 which, being in the same horizontal plane as the disk 39, is adapted at all times to contact the circumferential edge of the disk.

As indicated in the drawing, the upper end of 30 the shaft 16 projects beyond the disk 39 and is fitted with a lever 52. This lever is secured to the shaft 16 by a pin 53, and is of sufficient length to extend beyond the vertical face of the voting machine. The other end of the lever terminates 35 in a handle 54. Rotation of the lever about shaft 16 is limited by brackets 55 and 57 which are secured in any conventional manner to a cover plate 59 that encloses the mechanism above described. The brackets are recessed to receive 40 and mount resilient blocks 58. A spring 49 connects the arm 48 with bracket 57 and causes said arm to rotate about pin 47 and bring the roller 51 into pressure contact with the edge of the disk 39.

45 The structural features of the invention having been described, the operation thereof is as follows: When the voting machine is locked and the voter enclosing curtains are open, the lever 52 and disk 39 are in the position shown in Figure 1 of the drawing. It will be noted that pin 32, operable through movement of rod 37, is raised and projects up into the opening 46 of the disk 39. Rod 37 is connected with an entrance control knob (not shown). When a voter enters the booth, the 50 election official raises the entrance knob, thus moving bar 37 downwardly and withdrawing pin 32 from the opening 46. The voter may now manipulate the lever 52 for the purpose of closing the curtains and unlocking the machine for voting. When the lever has moved from the position 55 of Figure 1 to that of Figure 2, the curtains are closed. Further movement of the lever from the position of Figure 2 to that of Figure 3 brings the

inclined surface 43 of the disk 39 into contact with roller 51 of arm 48. Due to the spring 49, arm 48 rotates about the pin 47 and causes disk 39 and lever 52 to move practically unaided by the voter from the position of Figure 2 to that of 5 Figure 3. When the parts are in the position shown in Figure 3, the other pin 32 moves upwardly into the opening 44 of the disk, thus locking the lever 52 and preventing a voter from opening the curtains until he has cast his ballot. 10

Although applicant has shown and described only one modification of his invention, it will be understood by those skilled in the art that other adaptations thereof may be made without departing from the spirit and scope of the invention as defined in the hereunto annexed claims. 15

Having thus set forth my invention, what I claim as new and for which I desire protection by Letters Patent is:

1. In a voting machine having a curtain closing mechanism, manually movable means adapted to actuate said curtain closing mechanism, and further means for mechanically assisting in the movement of said means, said further means being effective when said manually movable means 20 has nearly completed its operation.

2. In a voting machine having a curtain closing mechanism, a manually operable lever on said machine for actuating said curtain closing mechanism, and means on said machine assisting in the 30 manual operation of said lever, said means being released by said lever when said mechanism has closed said curtain.

3. In a voting machine having a curtain closing mechanism, a voter operated lever for actuating 35 said mechanism, a disk joined to and rotatable with said lever, and means adapted to engage said disk during rotation thereof, said means assisting in the rotation of said disk and said lever.

4. In a voting machine having a curtain closing 40 mechanism, a lever on said machine, said lever being manually rotatable to actuate said mechanism, a disk joined to and rotatable with said lever, an arm pivotally mounted on said machine, spring means urging said arm into contact with 45 said disk, said arm being adapted to assist in the manual rotation of said lever at least during a part of the travel necessary to actuate said mechanism to close said curtain.

5. In a voting machine having a curtain closing 50 mechanism, a lever on said machine, said lever being manually rotatable to actuate said mechanism, a disk joined to and rotatable with said lever, a centrally pivoted arm on said machine adjacent said disk, spring means engaged with 55 one end of said arm, and a cam surface formed in the edge of said disk, the other end of said arm being engageable with said surface and, under tension of said spring means, serving to assist in the manual rotation of said lever during at 60 least a part of the travel necessary to actuate said mechanism to close said curtain.

ALVIN N. GUSTAVSON.
